UNITED STATES PATENT OFFICE.

GEORG LEOPOLD MUNDIGLER, OF MILWAUKEE, WISCONSIN.

TURBINE.

No. 822,069.

Specification of Letters Patent.

Patented May 29, 1906.

Application filed March 7, 1906. Serial No. 804,721.

To all whom it may concern:

Be it known that I, GEORG LEOPOLD MUNDIGLER, a subject of the Emperor of Austria-Hungary, and a resident of Milwaukee, in the county of Milwaukee and State of Wisconsin, have invented a new and Improved Turbine, of which the following is a specification.

My invention is an improvement in steam-turbines of the Parsons type, whereby I have reduced the cost and increased the efficiency of the same.

The details of construction, arrangement, and operation of parts are as hereinafter set forth, and illustrated in the accompanying drawings, in which—

Figure 1 is a perspective view of my improved turbine. Fig. 2 is a diagrammatic sectional view illustrating in detail the construction and arrangement of the steam-inlets and guides with reference to the radial shaft-blades. Fig. 3 is in part a longitudinal section and in part a side view of my turbine. Fig. 4 is an irregular cross-section on the line 4 4 of Fig. 3. Fig. 5 is an irregular cross-section on the line 5 5 of Fig. 3. Fig. 6 is a perspective view of one of the combined steam-inlet tubes and guides. Fig. 7 is a plan view of one of the conical sections of the inner casting of the turbine.

For ready distinction of the movable from the immovable parts of the turbine I will hereinafter designate the former by numerals and the latter by lower-case letters.

Referring to Figs. 1 and 3, *a* indicates the outer cylindrical casing of the turbine, and *b* the inner casing thereof. The latter is constructed in two duplicate parts, each being conical and the smaller ends of the cones being placed opposite and bolted together with an intervening annular partition *c*, which surrounds the shaft 1 and forms a steam-tight joint therewith. The outer ends of the inner casing-sections *b* are riveted at *d* to the ends and conical heads *a'* of the outer casing. Thus all the parts *a*, *a'*, *b*, and *c* are rigidly connected. The steam or other motive fluid is admitted at the top and center of the outer casing *a* by a pipe *e* and enters an annular space *x*, which exists between the casings *a* and *b*. Exhaust is provided for at each end of the casings by means of the conical hollow heads *a'*, the same having pendent portions *a''*, with which exhaust-pipes *f* are connected, the same leading to a common discharge *g*.

I will now describe the connection and arrangement of parts constituting the shaft-propelling media proper. As in the Parsons and other well-known forms of steam-turbine, the shaft 1 is provided with a series of circumferential rows of blades which are angular or curved in cross-section, the rows being commonly spaced apart to receive corresponding blades which are fixed to the casing. In my turbine, as in others of its general class, the steam or other motive fluid has axial flow; but I provide numerous inlets for the steam, whereby it passes from the annular steam-space *x* into spaces between the series of circumferential rows of blades that are fixed to the shaft 1. The means I employ for this purpose are tubes arranged in series *h i j k*. (See Figs. 2, 3, 6, and 7.) Since the inner casing-sections *b* are duplicates, both as to their construction and form *per se*, and the steam-inlet tubes and the blades connected therewith, it will be understood that the following description applies to one as well as the other. As shown in Fig. 6, each tube is slotted longitudinally, and it is arranged radially within the inner casing *b*, it being secured thereto at the outer end by a screw-joint or other preferred form of joint. In every case the arrangement of the tube is such that the longitudinal slot *l* is on the outer side—that is to say, on the side toward the adjacent conical end *a'* of the casing *a*—so that the steam admitted to the several tubes escapes in one direction and has an axial flow relative to the shaft 1. The first row of steam-inlet tubes *h* is arranged between the annular partition *c* and the adjacent row of shaft-blades 6, and the next row of steam-inlet tubes is arranged between the said shaft-blades 6 and the next row of shaft-blades 7. The inner ends of the tubes *h i* are preferably closed, as indicated in Fig. 3, and abut or are close to the periphery of the shaft 1. The length of the blades of the two series of shaft-blades 6 and 7 is also such that they extend to the inner periphery of the casing *a*. Thus the steam escaping from the tangential slots *l* (see Fig. 2) of the tubes *h i* enters the space between the shaft-blades 6 and 7 of the adjacent series throughout nearly their whole length. In other words, the escape of steam from the tubes *h i* and the reaction thereof on the shaft-blades 6 and 7 is throughout almost the entire length of the latter. With respect

to the remaining steam-inlet tubes j k and the shaft-blades with which they are connected and coat the case is different. Owing to the conical form of the inner casing b , it is apparent that the outer series of shaft-blades would require to be of great length or at least of greater length than is usually considered practicable. This is compensated for in the ordinary type of Parsons turbine by providing the shaft with a series of circumferential enlargements or "drums," upon the peripheries of which the blades are arranged, the wheel being thus distinguished by what are called "stages." I dispense with this arrangement and provide a freer escape of steam and also attain greater power as well as reduction of weight and cost of the turbine. I divide the longer blades into two parts or radial sections, as indicated in Figs. 3 and 4. Thus the blades 8, which are fixed radially on the shaft 1, extend to and are connected with the ring 9, and the bases of the entire series of outer blades 8^a are also connected with the same ring 9. In other words, the blades 8 and 8^a constitute two distinct series arranged in radial alinement, the outer ends of one and the inner ends of the other series being rigidly connected. Thus the blades of each series 8 8^a are practically short and have therefore corresponding strength. The same arrangement is adopted in respect to the outer series of blades 10 10^a. Thus, as shown in Fig. 3, the inner blades 10 are connected at their outer ends with the ring 11, and the bases of the outer blades 10^a are fixed in this ring. The ring 11 thus intervenes the two series of blades 10 10^a and rigidly connects the outer ends of the series 10 and forms a firm seat for the outer series 10^a.

The steam-inlet tubes j k of the two outer rows or series are practically of about the same length as the tubes of the inner series h i , and hence the steam which escapes from the tubes j h acts mainly upon the adjacent blades 8^a and 10^a of the two outer series of shaft-blades, access of steam from such tubes j k to the inner series of shaft-blades 8 and 1 being cut off by the rings 9 and 11. It is necessary, however, to provide fixed angular guides for steam between the inner series of shaft-blades, and these will be of a length equal to the distance between the inner ends of the tubes j k and the shaft 1. As indicated, (see Fig. 3,) guide-blades m are fixed at their outer ends in a ring n , that joins the inner ends of the tubes j k . There are thus two rings n , which are concentric with the shaft 1 and located equidistantly from the periphery of the conical inner casing b and constitute a firm support for the stationary guide-blades m , which intervene the shaft-blades. It will be seen that I arrange a series of rows of steam-inlet tubes h i j k around the inner casing b , the same projecting inward between the shaft-blades and being arranged with their slotted sides adjacent to the shaft-blades, so as to deliver steam directly thereto, and, further, that in the space where the conical form of the casing would otherwise necessitate too long shaft-blades the latter are divided into two radial series whose outer and inner ends are connected by a ring. Further, it will be seen that while the steam admitted to the first two tubes h i acts upon the adjacent shaft-blades 6 7 throughout their entire length the steam admitted to the tubes j k acts upon the outer series of divided blades 8^a and 10^a. A portion of the steam which reacts upon the blades 6 and 7 passes in an axial direction alongside the shaft 1 and acts upon the base portions of the shaft-blades 8 and 10, it being guided from one set to the other by the intervening fixed blades m , that project inward from the rings n , which connect the inner ends of the tubes j k . As will be observed from an inspection of Figs. 2 and 3, the steam-inlet tubes are not made of such diameter as to completely fill the space between the shaft-blades, but are made of about one-half the diameter of said space and are provided with tangential flanges o , which constitute so many steam-guides. In other words, the flanges project in such direction and are so arranged as to be parallel to the planes of the shaft-blades which may be brought directly opposite to them. The steam thus passes easily from the shaft-blades after acting thereon along the surfaces of the flanges o and around the adjacent portion of the tubes proper, and thus enters between the shaft-blades of an adjacent series and acts thereon, as before. It will be seen that the several tubes provide for a free admission of steam between and adjacent to the shaft-blades, so that a powerful reaction on the latter is obtained, and, further, that the arrangement of the tubes is such as to provide the freest escape of steam axially, while securing the highest effect due to reaction. In brief, I provide a clearance-space for steam, which enlarges from the inner to the outer end of the inner casing b and in which there are no surfaces directly opposing the progress of the steam save those by which reaction and power are obtained. In other words, the steam does not meet at any point with a radial shoulder or abutment, as in the case of the drum or stage construction of turbine, and by the provision of short outer steam-inlet tubes a free space is left adjacent to the shaft for passage of the steam admitted from the primary inlet-tubes or those located nearest the inner smaller end of the casing. Again, by the division of the inner casing into two duplicate parts which enlarge from their meeting ends outward the steam which enters each travels a comparatively short distance while acting powerfully

upon the shaft, and thus I obtain in power a much greater effect than would be practicable were the steam to traverse a casing having the aggregated length of both the conical sections.

5. What I claim is—

1. In a turbine of the class indicated, the combination with a rotary shaft and an outer casing, of an inner casing of conical form, the two casings being rigidly connected and a free steam-space intervening them, a series of steam-inlet tubes attached to and arranged radially in circular rows in the inner casing and provided with openings in the outer side, and a series of radial blades fixed on the shaft and intervening such tubes, substantially as described.

2. In a turbine of the class indicated, the combination with a rotary shaft having a series of radial blades, and an outer casing, of an inner casing of conical form, the two casings being separated to provide a steam-space, a series of steam-inlet tubes attached to and arranged radially within the inner casing, and provided with tangential lateral guides, substantially as described.

3. The combination with a rotary shaft having a series of radial blades, and an outer casing, of an inner casing having a double conical form and its enlarged ends being secured to the outer casing, an annular partition separating the inner casing-sections from each other, a series of steam-inlet tubes arranged radially in and secured to the inner casing, and provided with openings in their outer sides and tangential flanges on their rear or inner sides, substantially as described.

4. The combination with a rotary shaft having circumferential rows of blades, and an outer casing, of an inner casing having a conical form and secured to the outer casing, and a space intervening them for free admission of steam, a series of steam-inlet tubes attached to and arranged within the inner casing and provided with openings in their outer sides which are adjacent to the rows of shaft-blades, the shaft being of uniform diameter and the steam admitted at the several points by the several series of tubes passing axially and gradually expanding between the shaft and the gradually-enlarging space provided by the conical form of the casing, substantially as set forth.

5. The combination with a rotary shaft having a uniform diameter and the several series of radial blades, and an outer cylindrical casing, of an inner casing secured at its outer ends to the outer casing and having a conical form, steam-inlet tubes arranged radially within the inner casing and secured to the periphery thereof, the same being arranged in circumferential rows and spaced apart, and intervening the shaft-blades, several of the outer series of shaft-blades being di-

vided radially into two sets by a ring which 65 joins the outer ends of the inner set and forms a firm base for the outer set, substantially as described.

6. The combination with a rotary shaft and an outer casing, of an inner casing having a conical form and provided with several series of steam-inlet tubes having slots in their outer sides adjacent to the shaft-blades, the tubes nearest the inner end of the conical casing extending to the shaft and adjacent 75 the shaft-blades extending to the periphery of the casing, the succeeding or outer series of steam-inlet tubes extending but part way to the shaft, their inner ends being connected by rings and a series of steam-guides being 80 attached to said ring and projecting radially inward, and the shaft-blades which coact with such guides being correspondingly divided each into two sets, a ring intervening the two sets and connecting the outer ends of 85 the inner set and furnishing the base for the outer set, substantially as described.

7. The combination with a rotary shaft and an outer and inner casing rigidly connected thereto, of a series of steam-inlet 90 tubes having openings in their outer sides, the tubes of the several series being approximately uniform in length so that those in the outer rows are removed from the shaft, while the inner ones approach it closely, the outer 95 series being rigidly connected at their inner ends, and a series of guide-blades *m* being attached thereto and projecting radially inward, the shaft being provided with several 100 series of radial blades intervening a series of tubes, whereby steam admitted to the tubes at the inner end of the casing acts upon the adjacent blades throughout their whole 105 length while the steam entering the tubes of the outer series acts only upon the outer portion of the blades, substantially as described.

8. The combination with a shaft having a uniform diameter, of a surrounding casing which is tapered from one end to the other, a series of steam-inlet tubes arranged radially 110 within and secured to the periphery of the casing and provided with slots on the side toward the outer end of the casing, the tubes of the several series being of nearly the same 115 length, and a ring rigidly connecting their inner ends, and a series of inner tubes arranged radially within the ring and their outer ends attached thereto, a series of blades projecting inward from the ring and serving as steam-guides, the blades on that portion of the shaft 120 adjacent to the inner tubes being extended to the length permitted by the diameter of the casing and the blades on the outer portion of the shaft being formed in two sets with an intervening ring to which they are secured, 125 steam having thus direct passage from the inner end of the casing to the outer end parallel to the shaft, and another portion of the

- steam passing over the guides and blades adjacent to the casing, substantially as described.
9. The combination with a shaft having 5 radial blades and a surrounding casing, of steam-inlet tubes secured to the said casing and projecting inward between the shaft-blades and provided with openings on the sides which are close to the latter and on their 10 opposite sides with guide-flanges that extend to the row of blades in rear of the tubes, substantially as described.
10. The combination with a shaft having radial blades and a surrounding casing, of a series of steam-inlet tubes attached to and 15 projecting inward from the periphery of the casing and having on their outer sides openings for discharge of steam upon the adjacent blades, substantially as described.
